UNITED STATES PATENT OFFICE.

JOHN HAYS HAMMOND, JR., OF GLOUCESTER, MASSACHUSETTS.

SYSTEM OF LIGHT-BEAM CONTROL.

Application filed March 7, 1914, Serial No. 823,068. Renewed July 24, 1923.

To all whom it may concern:

Be it known that I, JOHN HAYS HAMMOND, Jr., a citizen of the United States, and a resident of Gloucester, in the county 6 of Essex and State of Massachusetts, have invented an Improvement in Systems of Light-Beam Control, of which the following description, in connection with the accompanying drawings, is a specification, 10 like characters on the drawings representing like parts.

This invention relates to light-beam control and in part to the control of lights, guides or signals by radiant energy, emitted 15 preferably as electro-magnetic waves from a distant control station.

In order that the principle of the invention may be readily understood, I have disclosed certain embodiments thereof in 20 the accompanying drawings, wherein—

Fig. 1 is a side elevation of a movable body, to which my invention may be applied;

Fig. 2 is a view, partially in side elevation and partially diagrammatic, of a system embodying my invention;

Fig. 2^a is a longitudinal sectional view of a valve employed therein;

Fig. 3 is a view, partially in side elevation and partially in vertical section, of a somewhat modified form of my invention; and

Fig. 4 is a detail in section of the valve shown in Fig. 3.

35 My invention particularly relates to the control of lights or signals, preferably mounted upon or carried by a movable body controlled from a distant station. The movable body may be of any suitable character, and preferably is one controlled by radiant energy of any desired nature, such as sound, light or electromagnetic waves, but which consists preferably of electro-magnetic waves emitted from the control 40 station. The movable body may be a water, land or air craft, such as a vessel, vehicle, or aeroplane, but herein I have represented my invention as applied to a vessel 1, which may be of any suitable type.

50 I have herein represented a vessel which is particularly adapted for scouting for the purpose, for example, of searching out mine fields at night, for directing lights against hostile or other ships to assist in firing from shore or other point, and for other purposes. This vessel is preferably controlled by elec-

tromagnetic waves from the control station, and for this purpose I have diagrammatically indicated the receiving antenna at 2, supported upon masts 3. Within the scope 60 of my invention, however, the vessel may be controlled by a crew, or otherwise. Upon the vessel, I position a light, indicated generally at 4, it being preferably a searchlight of sufficient power to send a 65 well-developed beam that may be readily detected from the observing or control station.

By the use of a well-developed beam, it is possible to determine and keep track of 70 the path of direction of movement of the vessel, so that if it deviates from its course, or a change of course is desired, this may be effected from a distant control station. In order, however, effectively to use the 75 beam of light as a means for determining the course of the vessel, it is highly important that means be provided to maintain the beam of light in a fixed, or substantially 80 fixed plane, so that the pitching and tossing 80 movements of the vessel, due to wave action, will not be transmitted to the light. If the beam of light partook of all tossing and irregular movements of the vessel, it would be extremely difficult to use the beam 85 of light for the purpose of determining its course, or for the purpose of throwing light upon some other object, toward which the vessel may be moving.

For this purpose, and in accordance with 90 my invention, I provide means to maintain the light in a fixed or substantially fixed plane, which may be and preferably is a horizontal plane, but which may be any other suitable plane at an angle to the horizontal. For that purpose, I provide standards 5, whereon is mounted a gimbal ring 6, preferably having mounted therein a second gimbal ring 6', that receives and supports the body 4 of the light. Upon a depending portion 7 of the searchlight 4, I mount one or more gyroscopes 8, which are constructed and mounted to operate in a horizontal plane or azimuth, or at some other suitable plane or planes, and thereby 95 100 105 to maintain the light 4 in such determined plane, irrespective of the motion of the vessel. The said gyroscopes may be of any suitable type, but preferably I employ an induction motor, in which the rotor is freely 110 suspended in space, so that it will maintain its fixed position when rotated at its proper

speed. If desired, the entire induction motor can be fixed to the frame of the searchlight, the latter being mounted in the gimbal rings 6, 6', so that the vessel may 5 rock or move with reference thereto.

Preferably I provide means whereby the emission of rays from the searchlight 4 can be controlled by light, sound, electromagnetic or other waves from the distant control station. For that purpose, I have herein represented mechanism whereby, upon the receipt of electromagnetic waves, a shutter or occulting mechanism upon the searchlight is operated to open the shutter and emit the beam of light.

Herein for this purpose I have represented the open, oscillatory receiving circuit at 9, this being connected to the winding or coil 10 of a closed oscillatory circuit of any suitable type, and shown as having therein a condenser 11, a stopping condenser 12, and a suitable crystal, or other detector 13 for electrical oscillations. At 14 I have indicated a sensitive relay, or other contact making device. These parts may be of any suitable construction not herein necessary more fully to describe or to indicate.

At 15 I have indicated a suitable battery or other source of electric energy, in circuit with the sensitive relay 14, and at 16 I have indicated a solenoid, the core or plunger whereof is formed as a valve 18 mounted in a valve casing 19 of a cylinder 20, and provided with a port 21 controlling the admission of fluid under pressure through the supply passage 22. For the purpose I preferably use air under pressure, which is admitted from a suitable tank or reservoir not herein shown.

40 Within the cylinder 20 is a piston 23, the piston rod 24 of which extends through the head 25 of the cylinder, and is provided with a rack 26 meshing with a gear 27 constituting a pawl carrier on which is pivoted a 45 spring pressed pawl 28. This pawl engages and is adapted to impart a step-by-step rotation to a ratchet 29 fixed to a valve 30 whereon said gear 27 is loosely mounted, said valve having appropriate passages as shown in 50 Fig. 2^a. Air or other suitable fluid under pressure is supplied to this valve 30 from a reservoir or other suitable source of supply through an inlet pipe 30'.

As herein shown the movement of the rack 26 in one direction acts through the pawl 28 and ratchet 29 to impart a quarter rotation to the valve 30, after which the rack, gear and pawl are returned to their initial position by a spring 31 surrounding the piston rod 24 within the cylinder 20.

In suitable relation to the valve 30 is positioned a cylinder 32, having therein a piston 33. At opposite sides of the piston, the cylinder is provided with ports 34, 35 connected by passages 36, 37 respectively to the

rotary valve 30, so that upon the receipt of impulses to which the closed oscillatory circuit is responsive, the piston 33 will be moved in one direction or the other.

The piston 33 is provided with a rod piston 38, the outer end 39 whereof is formed as a valve mounted in a valve casing 40, and having therein a port 41 controlling the supply of fluid under pressure through a passage 42 leading from the aforementioned source of supply. Connected to the other side of the valve casing is a passage 43, which leads to a cylinder 44 having therein a piston 45, the piston rod 46 of which is preferably provided with a rack 47 meshing with a pinion 48 which controls the operation of the shutter or other occulting mechanism or device for the searchlight 4. 70 75 80

Upon the admission of fluid pressure through the passage 37, the piston 33 is moved toward the left, viewing Fig. 2, so as to bring the port 41 into register with the passages 42, 43, and admitting the compressed fluid into the passage 43, thereby to operate the shutter or other device to permit the beam of light to be emitted from the searchlight 4. Upon the termination of the

impulse, or series of impulses by which the piston 33 was moved toward the left, so as to open the shutter, the solenoid 16 is de-energized, thereby closing the valve 18, and permitting the compressed air in the cylinder 20 at the left of the piston 23 to be discharged through a suitable exhaust port 18'. Thereupon the spring 31 returns the plunger 23 to its normal position, but without imparting reverse rotation to the valve 30. In this position of the parts, the shutter is open, and the beam of light is being emitted, such emission continuing until the receipt of a further impulse by the oscillatory circuit, whereupon the solenoid 16 is again ener-

I have herein represented a by-pass 51, leading from the cylinder 20 to the rotary valve 30, and permitting the air or other compressed fluid to pass from the cylinder 20 to the rotary valve 30 where it is exhausted, when the impulse is prolonged, and the piston 23 is moved to the right past the opening to said by-pass 51. When fluid

is admitted through the pipe 37 into the cylinder 32, it is exhausted from the other end of the cylinder through the pipe 36 and the rotary valve 30, and conversely when 5 fluid is admitted through pipe 36 it is exhausted through pipe 37 and said valve 30.

In Fig. 3, I have illustrated a modified form of means for maintaining the search light 4 in a predetermined plane, so that its 10 beam, when emitted, will remain fixed and will not partake of the motions of the vessel or other movable body or support whereon it is mounted. For that purpose, I have 15 represented said light as pivotally mounted in suitable supports 52, whereon also is pivotally mounted a pendulum 53, having a suitable weight 54 integral therewith, the pendulum being arranged to swing coaxially with the search light 4 and independently 20 thereof. The body of the search light 4 is provided with a ring, or cylinder 55, rigid therewith, and the pendulum 53 at its pivotal end is provided with a cylindrical valve 55' rigid therewith and mounted within the 25 ring or cylinder 55.

The ring or cylinder 55 is provided with five ports 56, 57, 58, 59 and 60, which are adapted to be brought into register with suitable passages in the valve 55', so as to 30 permit the compressed fluid to be admitted to one side or the other of a cylinder or other device, whereby, upon movement of the vessel, the searchlight 4 is correspondingly moved in the reverse direction, thus 35 maintaining it in its fixed horizontal or other predetermined plane, due to the action of the pendulum 53. While for this purpose I may provide any suitable construction, I have herein represented a passage 61, leading 40 from any suitable source of fluid under pressure, as for example compressed air.

The passage 61 is at all times in open 45 relation with the port 58 in the fixed ring or casing 55, whereby admitting such fluid to the valve 55'. The latter is provided with three passages 62, 63 and 64, so that upon relative movement of the ring or cylinder with respect to the valve, the fluid under 50 pressure may be admitted to either side of a piston and be exhausted from the other side thereof.

Leading from and in constant communication with the ports 57 and 59 are passages 55 65, 66, which lead to opposite ends of a cylinder 67 having therein a piston 68, the piston rod 69 whereof is pivotally connected by link 69' to a bracket 70, depending from and fixedly attached to the body of the searchlight 4. Thus, upon movement of the 60 vessel up or down, compressed fluid will be admitted through the supply pipe 61 into the proper passage 65 or 66, thereby to move the piston 68 to the right or left, viewing Fig. 3, thus moving the searchlight 4 up or 65 down, and thereby maintaining it in its

predetermined and preferably horizontal plane. When compressed fluid is supplied through the passage 65, it is exhausted from the passage 66, which, by means of the passage 64 in the valve 55', is in register 70 with the exhaust port 60, and conversely, when compressed air is admitted through the passage 66, it is exhausted through the passage 65 and the ports 57, 56. The passages 43, 61, 65, and 66 may be pipes of 75 suitable flexible material permitting the described stabilizing movements.

From the foregoing description, it will be evident that I have provided means whereby a beam or ray of light may be maintained 80 in a fixed or predetermined plane, irrespective of movements of the body whereon the source of light is mounted, so that said light may be used as a guide from which the distant observer may ascertain the source of 85 the vessel or other movable body whereon the source of light is located. I have also provided means controlled from the distant control station for emitting light only at the desired periods or intervals, the emission 90 of light thus being constantly under the control of the distant observer.

It will further be understood from the foregoing description that within the scope of my invention I may provide a guide or 95 signal of suitable type thereon, and may maintain the same in a fixed or predetermined plane, so that it will not partake of movements of the body whereon it is mounted.

Having thus described certain illustrative embodiments of my invention, I desire it to be understood that although specific terms are employed, they are used in a generic and descriptive sense and not for purposes of 105 limitation, the scope of the invention being set forth in the following claims.

Claims:

1. A system for controlling a light beam comprising in combination, a light-beam source supported upon a movable body subject to irregular movements, a controller, means controlled thereby and operatively connected to said light-beam source to stabilize said light beam, an electric circuit responsive to radiant energy from a distance for controlling the emission of said light beam, fluid pressure means controlled by said responsive circuit, and means operatively connected thereto to permit the emission of and to occult said stabilized light beam.

2. A system for controlling a light beam comprising in combination, a light-beam source supported upon a movable body subject to irregular movements, means for stabilizing said source, an electric circuit responsive to radiant energy from a distance for controlling the emission of said light beam, fluid pressure means controlled by 125

- said responsive circuit, and means operatively connected thereto to permit the emission of and to occult said stabilized light beam.
5. The combination with means for projecting a light beam, of means for stabilizing said light beam when said first mentioned means is mounted upon a body subjected to irregular movements, a shutter carried by said first mentioned means for controlling the emission of said beam, and means responsive to radiant energy for actuating said shutter.
10. 3. The combination with means for projecting a light beam, of means including a gyroscope for stabilizing said beam when said first mentioned means is mounted upon a body subjected to irregular movements, a shutter carried by said first mentioned means for controlling the emission of said beam, and means responsive to radiant energy for actuating said shutter.
15. 4. The combination with means for projecting a light beam, of means including a gyroscope for stabilizing said beam when said first mentioned means is mounted upon a body subjected to irregular movements, a shutter carried by said first mentioned means for controlling the emission of said beam, and means responsive to radiant energy for actuating said shutter.
20. 5. The combination with means for projecting a beam of light, of means for stabilizing said first mentioned means, when mounted upon a movable body, and means responsive to radiant energy for controlling the emission of a light beam from said first mentioned means.
25. 6. The combination with means for projecting a beam of light, of means including a gyroscope for stabilizing said first mentioned means, and means responsive to radiant energy for controlling the emission of a light beam from said first mentioned means.
30. 7. The combination with means for projecting a pencil of light, of means including a gyroscope for stabilizing said first mentioned means, and means responsive to radiant energy for occulting the pencil of light.
35. 8. The combination with means for projecting a pencil of light, of means including a gyroscope for stabilizing said first mentioned means, and means responsive to radiant energy to permit the emission of and for occulting the pencil of light.
40. 9. The combination with means for projecting a pencil of light, of means including a gyroscope for stabilizing said beam when said first mentioned means is mounted upon a body subjected to irregular movements, means for occulting pencil of light and means responsive to radiant energy for controlling said occulting means.
45. 10. The combination with means for projecting a pencil of light, of means including a gyroscope for stabilizing said beam when said first mentioned means is mounted upon a body subjected to irregular movements, means to permit the emission of and for occulting a pencil of light, and means responsive to radiant energy for controlling said emitting and occulting means.
50. 11. The combination with means for projecting a pencil of light, of means for stabilizing said first mentioned means when mounted on a movable body, and means responsive to radiant energy for occulting the pencil of light.
55. 12. The combination with means for projecting a pencil of light, of means for stabilizing said first mentioned means when mounted on a movable body, and means responsive to radiant energy to permit the emission of and for occulting the pencil of light.
60. 13. A system for controlling a light beam comprising in combination, a light-beam source supported upon a movable body subject to irregular movements, a gyroscope for stabilizing the light-beam whereby the direction of emission of light is independent of the orientation of said body, an electric circuit responsive to radiant energy from a distance and means included in and controlled by said circuit to permit the emission of and to occult said stabilized light beam.
65. In testimony whereof I have signed my name to this specification in the presence of two subscribing witnesses.
